US00D709862S

(12) **United States Design Patent**
Metzger

(10) **Patent No.:** **US D709,862 S**
(45) **Date of Patent:** **** Jul. 29, 2014**

(54) **TRANSMITTER HOUSING**

(75) Inventor: **Eric Metzger**, Franklin, WI (US)

(73) Assignee: **Badger Meter, Inc.**, Milwaukee, WI (US)

(**) Term: **14 Years**

(21) Appl. No.: **29/420,461**

(22) Filed: **May 9, 2012**

(51) **LOC (10) Cl.** **14-03**

(52) **U.S. Cl.**

USPC **D14/217**

(57) **CLAIM**

The ornamental design for a transmitter housing, as shown and described.

DESCRIPTION

FIG. 1 is a top perspective view of a transmitter housing, showing my new design;

FIG. 2 is a right side view thereof;

FIG. 3 is a front view thereof;

FIG. 4 is a top view thereof;

FIG. 5 is a left side view thereof;

FIG. 6 is a rear view thereof; and,

FIG. 7 is a bottom view thereof.

The broken lines depict environmental subject matter that forms no part of the claimed design.
